J. HOLLIS

TROLLEY MECHANISM

Filed Jan. 11, 1923

FIG. 1.

FIG. 2.

FIG. 3.

Inventor

Joseph Hollis

By Edward P. Alexander

Attorney

UNITED STATES PATENT OFFICE.

JOSEPH HOLLIS, OF CANTON, OHIO, ASSIGNOR, BY MESNE ASSIGNMENTS, TO THE OHIO BRASS COMPANY, OF MANSFIELD, OHIO, A CORPORATION OF NEW JERSEY.

TROLLEY MECHANISM.

Application filed January 11, 1923 Serial No. 611,923.

This invention relates to trolley mechanisms of the trolley retrieving and catcher types, examples of which are respectively disclosed in U. S. Letters Patent Nos. 1,056,742 5 (dated March 18, 1913) and 1,146,877 (dated July 20, 1915) granted to me; more particularly, the invention has to do with the lubrication of the shaft for the rope carrying or winding drum and other parts which may 10 be rotatably mounted thereon, in a mechanism of this character.

One object of the invention is to provide in a trolley mechanism having a rope carrying or winding drum, improved lubricant 15 holding and supplying means adapted to supply lubricant to the shaft on which the drum rotates.

Another object of the invention is to provide a rope carrying or winding drum with 20 a lubricant holding chamber and to so arrange this chamber that it can be readily re-filled from time to time.

Another object of the invention is to provide in a trolley mechanism, an improved 25 rope carrying or winding drum having a lubricant holding chamber and a duct leading thereinto through the drum wall, whereby the chamber may be readily filled.

A further object of the invention is to provide in a trolley mechanism an improved rope 30 carrying or winding drum having a lubricant holding chamber shaped to form a pocket so arranged that escape of the entire supply of lubricant in the chamber is prevented when 35 the drum comes to rest with the chamber disposed at the uppermost position in its path of movement.

Other objects of the invention will be apparent to those skilled in the art to which my 40 invention relates from the following description taken in connection with the accompanying drawing, wherein

Fig. 1 is a side elevation of a rope carrying or winding drum embodying my invention.

Fig. 2 is a section on the line 2—2 of Fig. 1.

Fig. 3 is a fragmentary side elevation, partly in section and enlarged to facilitate the illustration.

In the drawings, 1 indicates as an entirety 50 a drum adapted to have wound on it and unwound from it a rope (not shown), which is to be connected at its outer or free end to the trolley pole of an electric vehicle, such as an electric railway car. The inner end

of the rope is preferably connected to the 55 drum in the manner disclosed in my aforesaid Patent No. 1,146,877. The drum 1 may comprise a web 2 connected with a hub 3 at its inner portion and at its outer portion connected with a rim 4 having flanges 5, 5, extending around its opposite circumferential edges, the rim 4 serving as the wall on which the rope winds. The hub 3 is extended from either side of the web 2 to provide a relatively long bearing on the shaft, which preferably has connected to its opposite ends the casing members that house the drum and its controlling elements and operating spring (not shown). In the illustrated form of construction, one side of the web 2 is provided 70 with an annular series of ratchet teeth 6, with which a pawl (not shown) engages to control the rotation of the drum. The web 2, hub 3, rim 4 and flanges 5 are preferably formed integrally. 75

7 indicates a chamber provided on one side or face of the web 2, preferably that side opposite to the teeth 6, for receiving and holding a supply of suitable lubricant. The chamber 7 is disposed between the inner side of 80 the rim 4 and the hub 3, the walls of these parts co-operating with side walls 8, 8, each connected thereto, to form the chamber 7. 9 indicates the front wall of the chamber 7. The wall 9 is formed with an opening 10, 85 whereby, in manufacture of the drum, by casting, coring material may be removed readily from the chamber 7. The opening 10 is preferably round and the wall thereof is rabbeted, as shown at 10', to form a seat for a 90 disk 11. The disk 11 is preferably concavo-convex in shape, and after being positioned in its seat, it is hammered into a substantially flat condition, such operation serving to force its circumferential edge into intimate engagement with the wall of the opening 10 and thus close the opening in a liquid-tight manner. 95

12 indicates a duct formed in the hub 3 communicating with the chamber 7, and adapted to feed lubricant to the shaft for the drum 100 12. 13 indicates a duct formed in the rim 4 and leading into the chamber 7. It serves as an inlet through which lubricant may be supplied to the chamber 7 to fill it. The wall of the opening 13 is preferably formed with 105 screw threads so that a screw threaded plug 14 may removably close the opening. The plug 14 may be provided with a groove 15

in its outer end to receive a suitable tool, whereby the plug may be properly positioned and removed.

It will be noted that if the drum 2 comes 5 to rest with the lubricant holding chamber 7 in the uppermost position, as shown in Fig. 3, and remains idle in that position, the lubricant is apt to flow through the outlet duct 12 and in time entirely escape. To overcome 10 this disadvantage, I extend each of the side walls 8 to a point beyond a plane which is tangential to that portion of the hub 3 in which the duct 12 is formed, and then inwardly, the inner end of the wall being connected to the hub 3 at a point somewhat remote from the port 12; this construction serving to form pockets 16, 16, one at either side of the port 12. When the drum 2 comes to rest in the position shown in Fig. 3, the 15 pockets 16 will be below the level of the inlet end of the port 12. Accordingly, the pockets 16 will retain a portion of the lubricant, no matter how long the trolley mechanism may remain idle, to supply to the drum shaft when 20 the mechanism is again put into use.

It will be seen that in the construction of trolley mechanism and the drum herein disclosed, no removal of parts or disassembly of the mechanism is required to lubricate the 25 drum shaft. The construction is such that a quantity of lubricant can be provided in the supply chamber and the supply renewed from time to time in a ready and convenient manner. It will also be seen that the invention 30 is particularly applicable to types of trolley mechanism, such as herein referred to, wherein the main shaft or drum shaft forms the connecting element between the casing members and the removal thereof involves the dis- 35 assembly of substantially the entire mechanism. Where a considerable portion of the trolley rope is wound on the drum and it is desired to re-fill the chamber, all that is necessary 40 is to unwind a portion of the rope from the drum until the plug 14 is exposed and then to remove the latter. Accordingly it 45 will be seen that the chamber 7 can be re-filled from time to time in a quick and easy manner.

50 To those skilled in the art of making apparatus of the class described, many alterations in construction and widely differing embodiments and applications of the invention will suggest themselves without departing from 55 the spirit and scope thereof. My disclosures and the description herein are purely illustrative and are not intended to be in any sense limiting.

What I claim is:

60 1. In mechanism of the class described, the combination of a drum comprising a web,

hub and a rim on which a rope may be wound, a lubricant holding chamber disposed on one side of said web and connected with a supply duct formed in said rim and a discharge 65 duct formed in said hub through which the lubricant flows, the front wall of said chamber being formed with an opening which is rabbeted, and a concavo-convex disk fitting 70 said opening and adapted to be pressed into substantially flat condition to make the joint between its circumferential edge and the wall of said opening liquid-tight.

2. In mechanism of the class described, the combination of a drum having a web, a hub 75 and a rim on which a rope may be wound, a lubricant holding chamber disposed on said web and connected with a supply duct formed in said rim and a discharge duct formed in said hub through which the lubricant flows, the front wall of said chamber being formed with an opening which is rabbeted, and a concavo-convex disc fitting 80 said opening and adapted to be pressed into substantially flat condition to make the joint between its circumferential edge and wall over said opening liquid-tight, the said chamber arranged to surround the wall of said hub for substantially one half 85 its circumference to form a pocket on each side of the hub wall to retain the lubricant 90 therein when the drum stands with the chamber above said hub.

3. In mechanism of the class described, the combination of a drum, comprising a web, a hub and a rim on which a rope may be wound, ratchet teeth projecting to one side of the rim adapted to be engaged by a pawl to hold the drum against rotation, a lubricant holding chamber disposed on said web and connected with a supply duct formed in said rim and a discharge duct formed in said hub through which the lubricant flows, the front wall of 95 said chamber being formed with an opening having a shoulder, and a concavo-convex disc fitting 100 said opening and adapted to be pressed into substantially flat condition to make the joint between said circumferential edge and the wall of said opening liquid-tight.

4. In mechanism of the class described, the combination of a drum comprising a web, a hub and a rim on which a rope may be wound, ratchet teeth projecting to one side of the rim adapted to engage a pawl to hold the drum against rotation, and a lubricant holding chamber disposed on said web and connected with a supply duct formed in said rim and a discharge duct formed in said hub through 115 which the lubricant flows.

In testimony whereof, I have hereunto subscribed my name.

JOSEPH HOLLIS.
